VENTILATING APPARATUS

Richard G. Birkholz, Milwaukee, Wis., assignor,
by mesne assignments, to Midwest Manufacturing Company, Milwaukee, Wis., a corporation of Wisconsin

Application April 5, 1937, Serial No. 135,067

5 Claims. (Cl. 98—116)

The invention relates to ventilating apparatus, and has for an object to provide an improved ventilating device having a fan and having movable closure means which is actuated to open 5 position whenever the fan is running.

Another object of the invention is to provide improved closure operating means for the ventilating device.

A further object is to provide a ventilating device in which the fan is placed between two movable closures to house the fan, the closures being conjointly operable to open position.

A further object is to provide a ventilating device which can readily be assembled and installed, and which will permit easy access to the operating parts.

A further object is to provide a ventilating device which can be economically manufactured and which is efficient in operation.

20 The invention further consists in the several features hereinafter described and claimed.

In the accompanying drawing, illustrating certain embodiments of the invention,

Fig. 1 is a sectional elevation of a ventilating 25 device constructed in accordance with the invention, as the device appears when installed in a building wall, doors of the device being shown closed in full lines, and open positions of the doors being indicated by dotted lines;

30 Fig. 2 is an elevation of the device viewed from the intake side, parts being removed and broken away and parts being shown in section;

Fig. 3 is a sectional view of the device taken along the line 3—3 of Fig. 1;

35 Fig. 4 is a sectional view taken along the line 4—4 of Fig. 2;

Fig. 5 is a sectional view taken along the line 5—5 of Fig. 2;

40 Fig. 6 is a detail view of a door-operating mechanism, and

Fig. 7 is a view of the device modified for use with an intake duct.

In the drawing, 10 designates a square casing, preferably formed of heavy-gage sheet metal and 45 of a size to fit in a building wall between studs 11 of the wall, as indicated in Figs. 1 and 2. The casing is here shown to be supported by and between upper and lower headers 12 and 13 to which the upper and lower walls of the casing 50 are respectively secured by suitable means, such as nails 14.

A cast metal front plate 15 fits within the front or outer end of the casing and is provided with corner lugs 16 and attaching lugs 17, the 55 latter being riveted to the walls of the casing.

The front plate has a large central air opening 18 of generally circular shape, and the outer face of the front plate has a pair of spaced forwardly projecting flanges 19 and 20 near its margin forming a channel 21 between them of generally 5 rectangular outline to receive a packing strip 22. Caulking material 23 is inserted between the outer flange 19 and the front edge portions of the casing to seal the joint between them and also to seal the joint between the casing and a surrounding trimming frame 24 of the building.

An outer door 25 has a marginal flange 26 which seats in the channel 21 against the packing strip 22. The door is provided with lugs 27 at its upper edge swingably supported on hinge 15 pins 28 secured to forwardly projecting lugs 29 on the upper edge of the front plate 15. A lining sheet 30 of heat-insulating material is suitably fastened to the inner face of the door. The door is operated as hereinafter described.

20 The inner edge of the casing 10 is flush with the surface of the plaster 31 at the inner building wall, the casing being preferably arranged near the ceiling 32 of the room to be ventilated. A rectangular door frame 33, preferably of sheet 25 metal, is marginally flanged to bear against the plaster around the casing, and has a flange 34 which projects into the casing and defines a doorway 35. The door frame 33 is secured in place by screws 36 which are threaded into angle brackets 37 attached to the side walls of the casing by screws 38. A panelled door 39, preferably formed of sheet metal, fits in the doorway 35 and has clip angles 40 secured to its inner face and near its upper edge. The door is swingably mounted on 30 hinge pins 41 which are secured to the flange 34 of the door frame and extend through the clip angles 40.

35 A pair of brackets 42 are mounted on the inner sides of the upper and lower walls of the casing, and have detachably secured thereto by screws 43 the forked outer ends of a pair of respective vertical motor-supporting arms 44. The inner ends of the arms are of semi-cylindrical, concave shape to fit about a fan motor 45, the arms being 40 clamped about the motor by screws 46. The motor shaft extends horizontally and carries a fan 47 at its outer end disposed centrally in the circular opening 18 of the front plate 15. When the doors 25 and 39 are open, as hereinafter described, the fan exhausts the air from the room 45 to the outside atmosphere.

50 A duplex wiring receptacle 48 is secured in the casing at one of the lower corner portions thereof by screws 49. The fan motor has a cord 50 55

with a plug 51 for detachable connection with the receptacle. The casing is provided with knockouts 52 (one being shown in Fig. 1) to permit an armored cable 53 to be attached thereto at either the bottom wall or the side wall thereof for conducting current to the receptacle. The cable is also connected to a suitable wall switch 54 for controlling the motor.

The outer door 25 is urged to closed position by 10 a coiled spring 55 which is anchored at its inner end on a bracket arm 56 secured to a side wall of the casing, the other end of the spring passing through an opening 57 in the front plate 15 and being secured to a rod-like connector 58, Fig. 5, 15 which slidably fits in an opening 59 formed in the door. The outer end of the connector is pivotally secured to an arm or blade 60 which normally extends transversely of the connector and bears on the outer face of the door, being prevented from rotation by a stop 61 secured to the door. When access is desired to the fan motor and other parts within the casing, the spring tension may be released by swinging the arm 60 to horizontal position so that it may extend into 20 the opening 59. The inner door 39 is urged to its closed position by gravity.

The outer and inner doors are urged to open position by a door-operating mechanism now to be described. A housing 62 is secured by screws 30 63 to the lower portion of the side wall of the casing 10 opposite the receptacle 48. A small electric motor 64, preferably of the shaded pole induction type, is mounted in the housing by screws 65, and carries on its shaft a pinion 66 which 35 meshes with an intermediate gear 67 on a shaft 68 journaled in the housing. The shaft 68 carries a pinion 69 which meshes with another gear 70 on a shaft 71 journaled in the housing. The shaft 71 carries a pinion 72 outside the housing 40 meshing with a rack 73, the rack being held in mesh with the pinion by a headed screw 74 carrying a rack-engaging roller 75. The several pinions and gears form a reversible speed-reducing transmission. The rack passes through a 45 notched part of the opening 18 in the front plate 15, and one end of the rack is pivotally secured to a bracket 76 detachably secured by a screw 77 to the outer door 15. The other end of the rack carries a stop pin 78 to limit the outward movement 50 of the rack and door. A cord 79 is connected to the motor 64 and carries a plug 80 which is detachably plugged into the receptacle 48.

A lever 81 is journaled on a bracket arm 82 55 secured to the side wall of the casing above the receptacle 48. The short upper arm of the lever is connected to one end of a link 83, the link passing through an opening 84 in the front plate 15, and the other end of the link being pivotally connected to a lug 85 on the outer door 25. The long lower arm of the lever 81 carries a roller 86 bearing on the inner face of the inner door 39. By 60 this linkage the outer and inner doors will be opened simultaneously.

In the modified form of the invention shown in 65 Fig. 7, the inner door and door frame of the device are omitted, and the fan casing 10 is mounted between floor joists 87 of a building and adjacent the outer wall of the building. A duct 88 70 between the joists has an end fitting within the fan casing, the outer end of the duct having an intake register 89 opening in the ceiling 90 of the room to be ventilated. The construction of the device is otherwise the same as that of Figs. 75 1 to 6.

When the fan of the device of Figs. 1 to 6 is not operating, the doors 25 and 39 are both closed, the outer door being spring-urged against its seat 22 of packing material to exclude the weather, and to prevent the entrance of foreign matter and insects. The insulation 30 on the outer door minimizes heat transfer. The inner door also has an insulating effect and minimizes any condensation within the casing.

When the switch 54 is closed, the fan motor 10 starts in operation and simultaneously the door-operating motor also starts in operation and drives the rack 73 through the speed-reducing transmission. The rack 73 is thereby impelled outwardly, opening the outer door 25 against the 15 action of its spring 55 and also opening the inner door 39 by the linkage connecting the doors. The open positions of the doors are indicated in Fig. 4. The outward movement of the outer door is limited by the rack stop pin 78 engaging the roller 20 75, whereupon the motor 64 stops. The character of the motor permits the motor to remain safely in stalled condition for an indefinitely long period and without excessive power consumption. The fan exhausts the vitiated or odorous air from the kitchen or other room being ventilated, and the air current through the casing prevents the entrance of insects and also cools the fan motor and door-operating motor. When the 25 switch 54 is opened the fan motor shuts down, and the door-operating motor 64 is deenergized. The spring 55 then returns the outer door 25 to its closed position, and the inner door 39 returns to its closed position by gravity. The reversible transmission and motor 64 act to retard or brake 30 the closing movement of the doors. In both opening and closing, the doors operate smoothly and slowly, and without jarring or jerking, so as to minimize wear and noise and to prevent crystallization and breakage of parts.

The operation of the apparatus of Fig. 7 is generally the same as that of Fig. 1. The inner door, however, is ordinarily omitted from an installation of the type shown in Fig. 7.

In assembling the device, the door-operating 45 motor and its housing and attached cord are handled as one sub-assembly, and the fan motor and its supporting arms and cord are handled as another sub-assembly. After mounting these sub-assemblies in the casing the cords are plugged into the duplex receptacle 48. Either of these sub-assemblies can readily be removed for inspection, cleaning, or repairs. To remove the fan sub-assembly it is only necessary to loosen or detach the screws 43 and pull out the plug 51 55 from the receptacle. In cases where it is desirable or necessary to effect inspection or servicing from the outside, as in the installation illustrated in Fig. 7, it is preferable to release the spring tension at the connector 58, as hereinbefore described, and to release the screw 77 so as to permit wide opening of the outer door 25. Both the fan and door-operating mechanism can be removed from the outside.

What I claim as new and desire to secure by 65 Letters Patent is:

1. In a ventilating device, the combination of a casing, a door for said casing, door-opening mechanism including an electric motor and a speed-reducing transmission, a fan in said casing, an electric motor for said fan, means for 70 conjointly controlling said electric motors, and yielding pressure means for closing said door when said first-named electric motor is deenergized, said transmission and first-named motor 75

- forming a retarder for limiting the rate of closing movement of said door by said yielding pressure means.
2. In a ventilating device, the combination of a casing, a plate secured in an end of said casing and having an air opening, said plate having an outwardly projecting flange adjacent its periphery to form a caulking channel with the edge of the casing, and said plate having a channel 10 the outer wall of which is formed by said flange, packing material in said last named channel to form a closure seat around said opening, and a movably mounted closure engageable with said seat.
- 15 3. In a ventilating device, the combination of a casing, closure means for said casing, a fan in said casing, mechanism for operating said closure means including a rotary electric motor and a speed-reducing transmission, said motor moving 20 said closure means to open position and remaining in energized but stalled condition while said closure means is in open position, and yielding pressure means for closing said door when said motor is deenergized, said transmission and mo-
- tor forming a retarder for limiting the rate of closing movement of said door by said yielding pressure means.
4. In a ventilating device, the combination of a casing, a pivotally mounted door for said casing, said door having an aperture, a spring for urging said door to closed position, and a spring connector slidable in said door aperture and longitudinally adjustable in said aperture from the exterior of the door to release and reestablish the 10 spring tension from the exterior of said door.
- 5 5. In a ventilating device, the combination of a casing, a pivotally mounted door for said casing, said door having an aperture, a door-closing spring, a spring connector slidable in said aperture and having a slidable inner section secured to said spring and a pivotally joined outer section adapted to extend transversely of said inner section to engage the outer face of said door for resisting spring tension, said outer section being 15 alignable with said inner section and slidable in said aperture to release and reestablish the 20 spring tension from the exterior of said door.

RICHARD G. BIRKHOLZ.
